CLAIM

I claim the ornamental design for a shirt with cell phone pockets, as shown and described.

DESCRIPTION

FIG. 1 is a front perspective view of a shirt with cell phone pockets, showing a first embodiment of my new design;

FIG. 2 is a front elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a rear elevational view thereof;

FIG. 8 is a front perspective view of a second embodiment showing my new design;

FIG. 9 is a front elevational view of FIG. 8;

FIG. 10 is a top plan view of FIG. 8;

FIG. 11 is a bottom plan view of FIG. 8; and,

FIG. 12 is a right-side elevational view of FIG. 8, the left-side elevational view being a mirror image thereof.

The rear elevational views of both embodiments are identical.
